HURRICANE LAMP

Frank J. Santarpia, 44 Hilltop Road,
New Haven, Conn. 06515

Filed Oct. 4, 1965, Ser. No. 87,310

Term of patent 14 years

(Cl. D48—2)

Fig. 3

Fig. 4Fig. 5

FIG. 1 is a top plan view illustrating a hurricane lamp embodying my new design;

FIG. 2 is a side elevational view of the lamp;

FIG. 3 is a bottom view of the lamp;

FIG. 4 is an enlarged perspective view of the lamp; and

FIG. 5 is a sectional view taken on line 5—5 of FIG. 1.

I claim:

The ornamental design for a hurricane lamp, substantially as shown.
